Primary Examiner—Ruth McInroy**Attorney, Agent, or Firm**—Pearne, Gordon, McCoy & Granger LLP**[57]****CLAIM**

The ornamental design for a microwave oven front panel, as shown and described.

DESCRIPTION

FIG. 1 is a perspective view of a microwave oven front panel, showing our new design;

FIG. 2 is a front elevational view thereof;

FIG. 3 is a right side elevational view of a microwave oven front panel, the left side elevational view being a mirror image thereof;

FIG. 4 is a top plan view thereof; and,

FIG. 5 is a bottom plan view thereof.
